CLAIM

The ornamental design for a camera lens, as shown and described.

DESCRIPTION

FIG. 1 is a rear perspective view of a camera lens showing our new design.

FIG. 2 is a front perspective view of the camera lens.

FIG. 3 is a front view of the camera lens.

FIG. 4 is a rear view of the camera lens.

FIG. 5 is a left side view of the camera lens.

FIG. 6 is a right side view of the camera lens.

FIG. 7 is a top view of the camera lens.

FIG. 8 is a bottom view of the camera lens.

FIG. 9 is an enlarged portion view taken from encircled portion labeled, “FIG. 9,” in FIG. 1.

FIG. 10 is an enlarged portion view taken from encircled portion labeled, “FIG. 10,” in FIG. 1; and,

FIG. 11 is an enlarged portion view taken from encircled portion labeled, “FIG. 11,” in FIG. 2.

(Continued)

The broken lines in the figures show portions of the camera lens which form no part of the claimed design.

1 Claim, 11 Drawing Sheets
